(57) **CLAIM**

The ornamental design for a dual container drinking vessel with universal lid as shown and described.

DESCRIPTION

FIG. 1 is a front-side perspective view of a dual container drinking vessel with universal lid, showing our new design. FIG. 2 is a back view thereof.

FIG. 3 is a front view thereof.

FIG. 4 is a left-side view thereof.

FIG. 5 is a right-side view thereof; and,

FIG. 6 is a top view thereof.

The broken lines show portions of the dual container drinking vessel with universal lid that form no part of the claimed design.
